UNITED STATES PATENT OFFICE.

AUGUST FISCHER, OF WINCHESTER, ASSIGNOR OF ONE-HALF TO JAMES F. POTTS, OF WHITEHALL, ILLINOIS.

STRIKING MECHANISM FOR CLOCKS.

SPECIFICATION forming part of Letters Patent No. 336,996, dated March 2, 1886.

Application filed May 28, 1885. Serial No. 166,916. (Model.)

To all whom it may concern:

Be it known that I, AUGUST FISCHER, a citizen of the United States, and a resident of Winchester, county of Scott, State of Illinois, have invented new and useful Improvements 5 in Striking Mechanisms for Clocks, of which the following is a full and exact description, reference being had to the accompanying drawings, making part of this specification.

10 My invention relates to striking mechanism for clocks or other time-pieces; and it consists in a duality of bells of different tones, with hammers so arranged as to be operated by the time mechanism of the clock.

15 The object of the invention is to provide a simple and efficient striking mechanism for clocks provided with the twenty-four-hour system, by doing away with the necessity of consecutive strokes on one bell of a number corresponding with the hour indicated by the time-mechanism after the eleventh hour. I accomplish this by striking the several hours, as in the common system of twelve-hour clocks, upon the bell preferably of a light tone. When the 25 twelfth hour is reached, it is indicated by a single stroke on a bell of a different and preferably a deeper tone.

For the convenience of description, I will call the former the "light-toned" and the 30 latter the "deep-toned" bell.

In the drawings, Figure 1 is a front elevation of the striking mechanism detached. Fig. 2 is a side elevation of same. Fig. 3 is a detail of the wheel I and wires affected by it. 35 Fig. 4 is a detail of the bell-crank K' and oscillating pins L'. Fig. 5 is a detail view of wheel D and lever K. Fig. 6 is a detail view of wires L' and L² and arbor L and the levers K and K.'

40 On the shaft A of the minute-wheel is a lug, A', projecting far enough to engage the end of a crooked wire, B', which is rigidly attached to a loose shaft, B. Attached to this shaft are two other wires, B² and B³, the ends 45 of which are turned at an angle. The angled ends of B² are turned into the paths of a projecting pin on a small wheel, H, forming one of the chain of wheels comprising the striking mechanism. The end of B² extends under the 50 wire C', which is rigidly attached to the shaft C. Attached to the shaft C is the wire C²,

which is formed as shown in the drawings, one end protruding into irregularly-spaced perforations in the flanged periphery of the wheel D, and the angled end wire, C², which rests in 55 a single indentation in the periphery of the disk I. Both the shafts B and C are held in their normal positions by means of small wire springs.

The spring-wheel E and pinion-wheels F, 60 G, and H form a chain of wheels used in this mechanism. The wheel H engages a small cog-wheel on the shaft of the fan M. Attached to the shaft of the wheel G is a disk, I, having a single indentation cut in its periphery, and connected to the body of the wheel G by a small pin, I'. The wheel H is provided with a pin, J, extending from its side, as before referred to. The wheel D is provided with a perforated and indented flange, D', and spurs 65 on its periphery, as shown in drawings, the perforations lying in the path of the pawl end of wire C², the indentations in the path of the pawl end of lever K, the spurs in the path of the crank N. The lever K is so fulcrumed, as 70 shown in drawings, as to cause a long movement at the end of the lower arm for a short movement of the upperarm. Connected to the end of the lower arm of this lever is one arm of a bell-crank lever, K', the other arm of which 75 is slotted or forked, so as to hold free an oscillating pin, L'. The oscillating pin L' is pivoted in a shaft, L, in such manner as to allow the free end to engage the curved portions of the hammer-wire. Rigidly connected to the shaft 80 L is the wire L², the loose end of which lies in the path of the pin I'.

The bells O and P are of different tones—light and heavy, respectively. Poised over them are the hammers O' and P', the wires of 85 which are coiled around a shaft, as shown, so as to form a bearing, and turned up and over these coils to form a bearing for the oscillating pin L'.

The operation of the invention is as follows: 90 At every complete revolution of the minute-wheel the lug A' forces the crooked wire B' back until it passes it. In doing so, the shaft B is partially rotated, raising the end of the wires B² and B³. The angled portion of B² 95 resting under the wire C', raises it, thus partially rotating the shaft C. As the shaft C ro-

tates the wires C^2 and C^3 are thrown out of their engagement with the perforated flange-wheel D and the indented disk I , respectively. When the wheel G is thus released, the chain of 5 wheels begins to move, and they are regulated in such movement by the fan M . As the indentation in the disk I comes around, the wire C^3 would fall in engagement and stop the revolutions; but it is held from doing so by the wire 10 C^2 , the end of which, having no perforation presented in the flange D' , if the hour be more than one, cannot fall, as it rests on the solid part of the flange D' , for the wheel D has been moved forward one point by the small crank 15 N , which moves the wheel D by engaging the spurs on its periphery once in every revolution. As the disk I revolves, the pin I' engages the end of the wire L^2 and moves it back until it passes, when the wire falls suddenly 20 to its normal position. As the wire L^2 is thus acted upon, it partially rotates the shaft L , which moves the oscillating wire L' proportionately forward, which moves the hammer-wire that it rests against, throwing the hammer 25 back ready to strike. These actions and the reactions being simultaneous, when the pin I' releases the wire L^2 the hammer so acted upon falls suddenly, striking the bell to which it belongs. At every revolution of the disk 30 I this action occurs. The action is stopped by the bent portion of the wire C^3 falling into the indentation in the disk I , and the bent portion of wire C^2 into a perforation in flange D' of wheel D . 35 The action of levers K and K' is distinct from the chain of wheels, and is as follows: The upper arm of lever K rests against the flange D' , and is held there by a small spring, K^2 . When an indentation, which lies in the 40 path of the pawl end of lever K , comes to it, the pawl is forced into it. The end of the lower arm is thereby forced forward, carrying the connected arm of the bell-crank K' back and the slotted arm forward, forcing the 45 oscillating pin L' from the engagement with one hammer-wire to the other. When the pawl end of lever K is forced out of the indentation again, all these parts resume their former positions. When the pawl end of lever K 50 falls into an indentation, as before described, the pin L' engages the wire of hammer P' ,

poised over the heavy-toned bell P . When the pawl is riding the solid portion of the flange D' , the pin L' engages the wire of hammer O' , poised over the light-toned bell O .

55

The heavy-toned bell is used to strike the twelves in a number, and the light-toned bell the numbers less than twelve. Thus, when it is desired to strike the thirteenth hour, there will be two strokes—one on the heavy-toned 60 bell, marking the twelves, and one on the light, marking the additional numbers. At the twenty-fourth hour it will be indicated by two strokes on the deep-toned bell. The pawl end of the lever K will rest in an indentation 65 for one space of the movement of the wheel D , and will ride against the solid portion of the flange for the remaining strokes. It is obvious that I do not confine myself to the exact details of this system, as a succession of 70 rapid strokes on one bell might be used to indicate the number of twelves contained in a number, or one stroke on a bell and a pause, and the additional strokes on the same bell, thus marking the twelves and additional numbers, as in this invention. 75

Having thus fully described my invention, what I claim is—

1. In a striking mechanism of a clock or other time-piece, two bells or sets of bells of 80 different tones, two hammers or sets of hammers, and an oscillating lever engaging the ends of said hammers, and pivotally connected to a revolving shaft, L , and provided with a suitable mechanism for shifting it, substantially as and for the purpose set forth.

2. The combination of the wheel D , lever K , bell-crank K' with disk I , small crank N , pin I' , wire L^2 , pin L' , and hammers O' and P' , substantially as described.

90

3. The combination of the wheel D , wires C^2 and C^3 , B^2 and B' , lug A' , disk I , small crank N , pin I' , wire L^2 , pin L' , lever K , bell-crank K' , hammers O' and P' , and bells O and P , substantially as set forth and described.

95

In testimony whereof I have hereunto set my hand this 23d day of May, A. D. 1885.

AUGUST FISCHER.
